(57) **CLAIM**

(21) Appl. No.: **29/353,599**

The ornamental design for a charger base for a hand-held vacuum cleaner, as shown and described.

(22) Filed: **Jan. 12, 2010**

DESCRIPTION

(30) **Foreign Application Priority Data**

Jul. 13, 2009 (EP) 001151716-0001

(51) **LOC (9) Cl.** **13-02**

FIG. 1 is a perspective view of a charger base for a hand-held vacuum cleaner showing my new design.

(52) **U.S. Cl.** **D13/108; D32/31**

FIG. 2 is a left side view of the charger base according to FIG. 1.

(58) **Field of Classification Search** D13/107,

FIG. 3 is a right side view of the charger base according to FIG. 1.

D13/110, 133, 155, 184, 199; D14/251, D14/253, 432, 434; 320/107-115; 32/25, 32/31

FIG. 4 is a front view of the charger according to FIG. 1.

See application file for complete search history.

FIG. 5 is a rear view of the charger base according to FIG. 1.

(56) **References Cited**

FIG. 6 is a top view of the charger base for a hand-held vacuum cleaner according to FIG. 1; and,

U.S. PATENT DOCUMENTS

FIG. 7 is a bottom view of the charger base for a hand-held vacuum cleaner according to FIG. 1.
